UNITED STATES PATENT OFFICE.

LOUIS BLOCK, OF MAMARONECK, NEW YORK.

APPARATUS FOR CONDENSING AMMONIA.

1,210,141.

Specification of Letters Patent. Patented Dec. 26, 1916.

Application filed December 2, 1912. Serial No. 734,650.

To all whom it may concern:

Be it known that I, LOUIS BLOCK, a citizen of the United States, residing at Mamaroneck, in the county of Westchester and 5 State of New York, engineer, doing business in the borough of Manhattan, in the city, county, and State of New York, have invented a new and useful Improvement in Apparatus for Condensing Ammonia to Re- 10 duce It from the Gaseous to the Liquid Form.

I will describe it as receiving the gaseous ammonia in the usual condition at which it is received in this art, at a high tempera- 15 ture and at a pressure of say, twelve atmos- pheres.

I employ coils in the ordinary form, sometimes called trombones and cool them as usual by a descending current of cold water 20 on their exteriors except that I introduce the gas substantially at the bottom, and retain the liquefied ammonia mingled with the un- condensed gas in a gradually diminishing ratio as both together move rapidly up- 25 ward.

There is an economical means of trans- ferring heat known as "counter-current 30 heat exchanging"; my apparatus involves this. There is an advantage in ultimately receiving the condensed ammonia for re- frigerating and most other uses in the arts not only liquid, but also cold. My invention involves this.

My apparatus attains the heat exchanging 35 and thus cools the gas with less pipe sur- face and less water by reason of the hot gas entering at the bottom and giving up its superheat to the lowest pipes which the cool- ing water is just about to leave, and all the 40 way up the rapidly cooling gas finds itself more and more cool by being under the influence of water always a little cooler.

My apparatus delivers the liquid am- monia cooler finally than usual by reason 45 of its leaving by an upper pipe which is bathed in the latest received water. And it attains the more rapid transfer of heat by reason of using the liquid ammonia as an internal condensing agent and conveying 50 the heat by such medium to the iron and thus to the cold water outside. I esteem these important features of the apparatus.

In the working of my invention the am- monia enters the coils in the form of hot 55 gas near the bottom. Its velocity being

slowed down the momentum affords the requisite lifting power urging the mixture up the slight steps. In rising, it parts first with its superheat, the heat which it may chance to have above that required to maintain its vaporous condition, and afterward with the latent heat which has before maintained its vaporous condition, which we may continue to call gaseous.

In some condensers now used in the arts, 60 the hot gas enters the lowest pipe but it is only for the purpose of removing the super- heat and the condenser pipe is immediately extended upward carrying it to near the top, after which as in ordinary condensers, the 65 gas descends through the zig zag coil and the liquefied gas is discharged near the bot- tom. In some modifications the gas enters the lowest pipe and is caused to travel up- 70 ward. In such however, the pipes have been 75 provided with liquid drains so that the liquid ammonia which forms by condensa- tion is drained off as soon as it forms.

I have discovered that it is practicable to cause the gaseous ammonia and the liquid 80 ammonia which is produced by its con- densation to mix together, and by having the ascent sufficiently gradual to cause the mixture to move upward by momentum in 85 the whole of the several pipes and return bends, the proportion of the dense liquid being small in the bottom pipe and growing larger as the mixture rises, until all is liquid, 90 all is condensed ammonia, and is carried away as such from the upper portion of the coil, cooled at last to near the temperature of the cooling water. My apparatus utilizes 95 this discovery and adds some further fea- tures of importance.

The invention insures a wet condition of 100 the inferior surfaces of all the pipes and return bends and thereby promotes the active transfer of caloric from the contents into the metal and also gives a great increase to the area of the condensing surface in a form which is distributed throughout the whole space in the interiors of the pipes and return bends by using the liquid ammonia thus developed to condense succeeding in- stallments of gaseous ammonia.

The gas rises in globules or bubbles, con- 105 stantly growing smaller. The previously 110 condensed ammonia in its form of a dense liquid fills the spaces and applies against the exterior of practically every globule of

the gas, and the interiors of the pipes and return bends. The previously condensed ammonia serves as a heat conveying medium between the bubbles of gas and the inner surfaces of the metal. The act of condensation is proceeding over the whole of the great surface presented by these small globules of gas. The heat moves outward from the whole surface of all the bubbles into the 10 dense liquid ammonia. The liquid in its turn circulates actively against the inner surface of the inclosing metal, the transfer this time being from a liquid to a metal and the heat moves out with greater efficiency 15 from the surface presented. The heat leaves the gas and goes into the liquefied ammonia, making part of the latter gaseous, this travels rapidly forward and upward in contact with the inclosing cool metal and giving up its heat thereto, which escapes through the metal to be carried away by the water outside. Meanwhile, the gaseous ammonia enters the next pipe above, attacking 20 another unit of liquefied ammonia, and similarly exchanging conditions in that more advanced stage, and thus repeating. It will be observed that the exteriors of the metal parts, the coils and the return bends are 25 cooled by the descending colder water in the same manner as has long been practised in other gas condensers, except that the work is so manipulated that the coldest water strikes first on the coldest pipes afterward on pipes below, which are slightly warmer, and so 30 on, giving the advantages of the much valued counter-current heat-exchanging.

I will be as specific as I am able in order to present information in regard to the increased activity of the transfer of heat by 40 my apparatus. Experiments in the arts have established that liquefied ammonia absorbs heat from other liquid through metal (or when oppositely conditioned imparts heat to other liquid through metal) five 45 times as fast as gaseous ammonia. With water to water the transfer of heat for each square foot of surface and each degree Fahr. difference of temperature is 300 B. T. U. per hour, while with gas to water as in ordinary 50 ammonia condensers the transfer is only 60 B. T. U. per hour. We cannot know all the action under different conditions, but it is largely dependent upon how fast the heat of the liquid ammonia can. 55 after it has entered the iron, be transferred through the metal to the water flowing over it. Neglecting the resistance to the flow of heat through the thin metal which is obviously the same in each, the transfer of 60 heat from the ammonia bubbles to the liquid ammonia surrounding them is 60 B. T. U., and the transfer of heat from the dense liquid to the metal inclosing it and thence to the water outside, liquid to liquid, has by 65 published experiments in other arts been

found to be 300 B. T. U. per hour. It appears that the two transfers of heat in my apparatus are each made at a rate occupying only about $\frac{1}{5}$ of the time which is required by the old practice for its single 70 transfer. Thus reckoned mathematically the efficiency of mine is greater than the ordinary in the ratio of 5 to 1. It is not important that these figures be exactly correct, I give them as the nearest now available. 75

The following is a description of what I consider the best means of carrying out the invention on a large scale suitable for restoring the ammonia used in refrigerating 80 air, or brine, or for ice-making purposes.

The accompanying drawings form a part of this specification.

Figure 1 is a perspective view of the main parts. Fig. 2 is a side elevation of the same 85 form with water supply properly added, and Fig. 3 is a diagrammatic side view giving the most completely developed form of the main portion of the apparatus employed. Fig. 4 is on a much larger scale. It is a 90 longitudinal section of a portion of two of the horizontal condenser pipes and the connecting return bend.

Similar letters and marks of reference indicate corresponding parts in all the figures. 95

I show iron pipes, preferably galvanized pipes, connected together as usual, in sections with return bends. I show four sections each sixteen pipes high to obtain sufficiently extended condensing surfaces at the 100 highest ordinary temperature of the air and water. I introduce the hot gaseous ammonia near the bottom of each section and cause it to move upward therein, and to flow away at or near the top in the form of dense 105 liquid.

Referring to the letters of reference on the illustrative drawings, Fig. 1, A¹ and the vertical tier of pipes associated below are horizontal iron pipes, connected by U-shaped 110 return bends or couplings by which all the pipes in each tier are united into what is termed sometimes a zig zag coil or trombone coil. As shown four coils are mounted side by side at a convenient distance apart. 115 In these the condensing of the gaseous ammonia and also the preliminary cooling of it, and the subsequent further cooling of the liquefied ammonia, is effected in one continuous series, rising from the pipe A²⁰ at 120 the bottom to the pipe A¹ to the top, from which latter level the ammonia is delivered in a liquefied and cold condition.

B is a horizontal transverse pipe or header which receives the gaseous ammonia 125 through a vertical pipe B^x and an intermediate check valve C and distributes it to the several coils through the means of descending pipes B', etc., one for each coil, controlled by cocks or valves B² and joined to 130

the zig zag coils with proper care to maintain tight joints and allow for repairs as ill be understood.

5 D' are horizontal pipes connecting the uppermost pipe in each of the several coils A with the header D. The header takes away the condensed ammonia, receiving it through the branches D' as shown. D² are stop valves or cocks in these branch pipes. 10 They are always open when the condenser is working.

There is a separate trough or slotted pipe for distributing condensing water over each of the coils, with a separate supply for each, 15 indicated in Fig. 2, where M is the supply pipe and N the trough for each.

The gaseous ammonia flows inward continuously past the check valve C into the header pipe B and down through the several 20 pipes B' to near the base of each coil. It flows upward by a zig zag course through the condenser by moving alternately to the right and left through the several level pipes A¹, A², etc., and outward through the several 25 U-shaped return bends connecting them, till it is near the top, becoming condensed and giving its heat ultimately to the shower of cold water descending on the exterior from pipe to pipe. All the contents of each pipe 30 is an agitated mixture of liquefied and gaseous ammonia and all is moving upward through the several return bends and through the level pipes which connect them.

An active mixing of the gaseous ammonia 35 with the liquefied is useful, and the arrangement shown attains that. It also attains more. I provide each of the several return bends with a transverse ridge a which in my experiments has been cast integral with 40 the bend as shown clearly in Fig. 4. This serves as a dam holding in each of the pipes A¹, A², etc., about a $\frac{1}{3}$ full of the denser mixture. The whole in each pipe has an upward trend.

45 The arrangement is certain to keep all parts of the interiors of all of each pair of pipes A¹, A², etc., down nearly to the bottom, thoroughly wet with liquid ammonia. It is also intended to keep all the upper portions 50 of the interior spaces filled with an actively circulating mixture, and to also keep the extreme lower part of each pipe and bend the wettest.

55 There is a liability to difference of pressure in the gaseous ammonia in the several coils which might produce irregular working conditions. This is avoided by providing an equalizing header E, which communicates by a branch E', with the liquid header 60 D, and also communicates independently with the several coils A by branches E'. It is sometimes desired to allow the entering gas to flow backward from the pipe B past the check valve C. To attain this I provide 65 a bypass pipe B⁴, controlled by a cock or

valve B⁵. It is sometimes required to drain the ammonia entirely from the coils. To attain this I provide the connecting pipes D³, with valves D⁴, one for each, connecting low points in the coils A with the drain-header D⁸ which latter is controlled by a cock or valve D⁹, and connects with discharge pipe D⁷. This and valve D⁴ can be opened to facilitate drainage at intervals for cleaning or other purposes. These are 75 ordinarily kept closed.

The name drain header does not suggest all the functions of the header D⁸. A pipe D⁵ leads from the pipe D⁶ and from its position is certain to be always supplied with liquefied ammonia from above. I provide a valve D¹⁰ on such pipe, which connects the drain-header D⁸ with the pipe D⁶, at will. Under some conditions I work with that valve open. Valve D⁹ in pipe connecting 80 drain-header D⁸, with discharge pipe D⁷, is then kept tightly shut. By opening valve D¹⁰ the liquefied ammonia from above, descending through the pipe D⁵, keeps the drain-header filled with liquid ammonia. 85 By opening either one or all of the valves D⁴ to a small extent, the liquefied ammonia will ascend through each and mingle with the gaseous ammonia, which is being introduced. The effect is to supply some liquefied ammonia, when it is judged expedient, at an early stage in the movement of the gas 90 through either or all the coils of the condenser and make the lower pipes and returns more efficient. I provide also a trap to prevent backward movement of the liquefied ammonia through the introduction passage which is useful in addition to the check valve C or may if required, serve alone. This construction attains the end both of a trap alone 95 or of a trap with the addition of a check valve to prevent any accidental backward movement of the liquefied ammonia when the condenser is idle. The check valve C tends to make a positive holding means, but 100 when in order to relieve the incoming gas from the slight resistance always due to the weight of a check valve, or when for any reason it is desired to operate the condenser without such valve being effective, the end 105

110 v be attained, as above suggested, by constructing the bypass pipe larger and setting the bypass valve B⁵ open. Then the horizontal pipe B and its connections including the upright pipe B^x and the corresponding descending pipes B', serve as a trap and attain 115 the important end of preventing any back flow of the ammonia under any pressure usually attained in practice. I provide also a trap for the header D which carries the liquefied ammonia away to prevent any blowing through of uncondensed gas. The pressure of the gas in the trap is the same 120 as the pressure in the upper pipe A the condenser, the passage by which the liquefied 125 ammonia passes. The trap is controlled by a valve 130

ammonia leaves, and the same as the pressure in the liquid receiver, located on a lower level, to which it is delivered, and since the pipe D^6 of the trap leads first down and then up, and is connected by branch E^3 controlled by the cock E^4 with equalizing header E a discharge of gaseous ammonia is prevented while the easy discharge of liquid ammonia is assured.

10 A pipe h , connects the top of the liquid receiver with the equalizing header E . It equalizes the pressure in the liquid receiver and the upper part of the condenser, and insures a free flow of liquid ammonia from 15 the latter to the receiver.

P is a receiver or storage tank supplied with connecting pipes and controlling cocks standing in the relation shown ready to supply more ammonia or store some whenever 20 required. It should be of sufficient capacity to receive and temporarily store any excess and supply any temporary deficiency. It is provided with a gage-glass which shows plainly how much liquid ammonia there is 25 in the receiver at all times.

The pipe h^1 is a pump-out pipe, it connects pipe "h" with the suction side of the refrigerating machine and by opening valve h^2 after having closed valve E^2 in the 30 branches E^1 of all the condensers not to be pumped out, and closing valves E^4 , D^2 , D^{11} and h^3 , leaving valve E^2 on any condenser coil which is required to be pumped out, open, such coil for purpose of repair or for 35 any other reason, can be emptied of ammonia.

G is the ordinary air drum into which any air or noncondensable gases, which gather in the apparatus may rise through the cock 40 f , and at long intervals may be blown out through the cock f^1 .

In Fig. 3 two features are developed, neither of which has been previously described. In this figure I show that the 45 discharge of the liquid may be at a point lower than the uppermost pipe of the condenser and that the entrance for the gas may be at a point above the lowermost pipe of the condenser. When constructed as shown 50 in Fig. 3, the liquid is carried upward and then downward to be discharged, and all of that portion of the condenser, that is all of the pipes above the point of discharge, serve as a liquid cooler. As these pipes are the 55 first in the path of the shower of water falling over the condenser their contents will be subjected to the coolest water and as it is condensed liquid, out of contact with gas, its temperature will be lowered to an extent 60 greater than is possible in the construction shown in Fig. 1, or in any other similar device, where uncondensed gas may and most likely is still intermingled with the liquid as both together are traveling upward. I 65 have found that where a multiplicity of

units are connected to a single header the velocity of gas due to its pressure and to the lower temperature and consequent lower pressure within the condenser will, when the units are operating below their capacity, 70 cause the units nearest to the point of entrance into the header to receive not an equal proportion of the gas, but a greater quantity, and as a consequence thereof certain of the units will do but little or no work. I might 75 provide against this by throttling the entrance into each unit by means of a valve B^1 or by other means. But this would require an adjustment of the valves whenever a change occurred in the amount of work to 80 be done by the condenser. I have arranged an automatically operating means for causing an even distribution of the hot gas in all of the units. The means that I have employed is to cause the gas to enter at a point 85 above the lowermost pipe of the condenser. It will then be forced to travel downward in parallel flow with the water, through a small number of pipes and will not therefore be immediately subjected to the influence of 90 the lower pressure within the condenser which as before described will increase its velocity. The hot gas will be forced by the pressure to which it is subjected to pass downward through pipes that are subject to 95 the influence of the warmest water. Here it parts with its super-heat, but I do not intend nor do I believe that condensation will take place in these pipes. The gas is then passed 100 upward to the lowermost pipes of the condensing zone and although an increased velocity may take place by the desire of the gas to fill the unoccupied space in the condensing zone and due to the fact that it now travels in counter current to the cooling water, this increased velocity will not affect 105 the gas passing downward in the lowermost pipes to any material extent, as the friction alone within the pipes will materially decrease the possible velocity and thus a proportionate even distribution of gas in a number of units is accomplished. I consider 110 both of these features important as they materially add to the efficiency of my construction.

Modifications.—Part or parts may be omitted, I do not limit myself to the exact form of the return bend shown in Fig. 4. I can use a smaller dam and a less distorted form of the castings constituting the return 120 bend. I can work with the other portions of the invention and the return bends now in the market, but I prefer the one shown with the dam for the reason among others that it will hold liquid ammonia in the upper pipes 125 when the condenser is idle, and thus have it ready for instantaneous operation all the time. In the form shown in Fig. 3, the upper pipes are used as a liquid cooler, which while directly connected with the condenser 130

serves for liquid cooling alone after the condensing is completed. Good results may be obtained by introducing the gas above the lower pipe and discharging it in liquefied 5 condition either at the top of the coil or near the top as shown in Fig. 3.

I do not limit myself to the exact form of the trap shown, to prevent the discharge of uncondensed gas, I claim any device connected to the delivery side of the condenser 10 which will arrest the uncondensed portion of the gas.

I claim:

1. A gas condenser comprising a plurality 15 of superimposed horizontally arranged pipes having the gas inlet approximately at the bottom and the final liquid discharge outlet above the highest condenser pipe and a trap connected at the top for preventing the discharge of unliquefied gas and for maintaining liquid in the condenser, as and for the purpose set forth.

2. A gas condenser comprising a plurality 25 of superimposed horizontally arranged pipes having the gas inlet approximately at the bottom and the final liquid discharge outlet above the highest condenser pipe and a trap connected at the top for preventing the discharge of unliquefied gas and for 30 maintaining liquid in the condenser and means for preventing back flow of said liquid ammonia out of the inlet passage as and for the purpose set forth.

3. A gas condenser comprising a trombone 35 coil having the gas inlet substantially at the bottom and the liquid outlet substantially at the top with means for preventing the discharge forward of unliquefied gas, and a valved drain at the bottom of the condenser to empty the same of liquid when required, in combination with means for showering water over the condenser.

4. In ammonia condensers, trombone coils 45 of pipe, means for introducing the gas near the bottom thereof, means for taking the liquid away near the top, a header connected with the several coils, a trap on the pipe which leads to the liquid away, and means for preventing siphoning of the liquid 50 through the trap, in combination with means for showering water over the coils.

5. In an ammonia condenser, trombone coils of pipes and means for bringing the gas from a higher level to the lowest pipes 55 thereof, in combination with means by the drum "G" at a higher level and a connecting passage for purging the condenser of non-condensable gases, a check valve arranged for positively preventing any return flow, a pipe arranged for taking away the 60 condensed and cooled ammonia at a high point, and a trap to prevent accidental forward flow of uncondensed gas and means for showering water over the coils.

6. A gas condenser comprising a plurality

of superimposed horizontally arranged pipes as an ordinary trombone coil, with connections as shown so that the gas enters substantially at the bottom pipe and the liquid produced leaves at a high point and means for preventing back flow into the introductory passage, in combination with a liquid receiver and a connection between the condenser and the liquid receiver, and means for showering water over the condenser. 70

7. A gas condenser comprising a trombone coil with connections to trap the liquid produced against flowing backward into the introductory connection, and to trap any remaining uncondensed gas against forward flow, in combination with a liquid cooler 80 above the condenser and connected with the same and means for showering water over the liquid cooler and condenser.

8. In a condenser having trombone coils 85 with means for moving the contents upward therein, means for flowing water down the outer surfaces, and dams within the passages of said coils adapted to obstruct the flow of liquid along the bottom of the several pipes and to hold them always partially filled with liquefied ammonia.

9. In a condenser having trombone coils 90 with means for moving the contents upward therein, means for flowing water down the outer surfaces, and dams within the return bends of said coils adapted to obstruct the flow of liquid along the bottom of the several pipes and to hold them always partially filled with liquefied ammonia, a raised top 95 over each dam so as to keep the passage substantially uniform in cross section, with each dam made integral with the corresponding return bend and the bends formed with means for joining tightly to the corresponding pipes as herein specified. 100

10. In a condenser having substantially horizontal pipes and return bends and means for showering water down their exteriors and means for moving their contents in another direction, the combination therewith of dams within said pipes for retarding the internal flow of the liquid and mingling the gaseous ammonia with the liquefied by compelling the latter to flow over such dams, 110 and the several pipes enlarged by raising the tops of each where it extends past a dam. 115

11. In gas condensers having a plurality of pipes a pipe D⁵ and valve D¹⁰ connecting the liquefied gas discharge with the hot gas inlet and arranged to allow a part of the liquefied ammonia to flow backward and mingle with the succeeding installments, in combination with a valve D⁴ arranged to perform the alternate functions of controlling the 120 flow of liquid into a pipe at will, or when required, draining the condenser. 125

12. In ammonia condensers means for introducing gas near the bottom thereof, means for causing said gas to pass down- 130

ward, then upward therein and for discharging the liquefied gas at the top.

13. A gas condenser having means for discharging the liquefied gas at the top in combination with a liquid cooler mounted over said condenser and connected to the upper pipe thereof.

14. In ammonia condensers means for introducing gas near the bottom thereof, means for causing said gas to pass downward, then upward therein and means for causing the

liquid to flow upward and then downward to be discharged below the top of said condenser.

Signed at New York city, in the county 15 and State of New York, this twenty-third day of November, A. D. 1912.

LOUIS BLOCK.
